W. R. BERRYMAN

SHUTTLE BOBBIN

Filed Aug. 28, 1922

William R. Berryman, Inventor
By his Attorney
Thomas Howe

UNITED STATES PATENT OFFICE.

WILLIAM R. BERRYMAN, OF BROOKLYN, NEW YORK.

SHUTTLE BOBBIN.

Application filed August 28, 1922. Serial No. 584,633.

To all whom it may concern:

Be it known that I, WILLIAM R. BERRYMAN, a citizen of the United States of America, residing at Brooklyn, county of Kings, and State of New York, have invented new and useful Improvements in Shuttle Bobbins, of which the following is a specification.

This invention relates to the bobbins employed in the shuttles of sewing machines and the like. It is contemplated that it will be chiefly useful in connection with such applications, but is not limited thereto.

In unwinding the thread or twine from a bobbin, the thread or twine is some times drawn in between the bobbin head and the end of the roll of twine or cord and, the cord becoming gripped, stoppage or breakage of the apparatus or thread occurs with resulting trouble or loss of time. This is especially apt to occur in those forms of bobbin wherein a cylindrical portion has the thread or twine wound upon it and the completed bobbin for use in the shuttle is formed by affixing end heads to the cylindrical portion, because in the operation of the apparatus the end heads may work slightly away from the ends of the thread or twine roll, even if they are pressed tightly against it in the first place, and spaces are thereby formed which render the thread or twine extremely liable to become caught in the unwinding operation. Bobbins with removable end heads as described are frequently made use of for the reason that the thread and twine manufacturer usually winds his thread upon a hollow pasteboard cylinder and then end heads are added, these end heads comprising projections which telescope within the ends of the pasteboard tube and friction between the parts is depended upon to hold the cylinder and end heads together.

It is the main object of the invention to prevent catching of the thread or twine as referred to and to this end the inner side of the end head is made cushioning or resilient so that it will conform to and bear against the end surface of the thread roll on the bobbin so as to fill any crevices which otherwise might exist between the thread roll and end head and, in case the heads are removable and are backed off from the roll as before referred to the cushioning will act to fill the crevice which would otherwise

be formed and the thread is thus prevented from entering a clearance or crevice between the end of the thread roll and the bobbin head, and catching of the thread as above referred to is avoided.

Other and ancillary objects of the invention will appear hereinafter.

In the accompanying drawings which illustrate the invention—

Fig. 1 is a side elevation of a wound bobbin embodying the invention;

Fig. 2 is a side elevation partly in section, partly broken away, of a shuttle having the improved bobbin mounted therein;

Fig. 3 is a perspective view of an end head for the bobbin and cushioning means for the inside thereof; and

Fig. 4 is a perspective view of the cylinder or spool of the bobbin.

Referring to the drawings, the bobbin therein shown comprises a hollow cylindrical spool portion 1, preferably of pasteboard, upon which the thread or twine 2 is wound in any of the well known ways of winding thread upon a spool. The shuttle 3 may be of any well known or suitable construction having a bobbin recess 4 into which projects a shaft 5 whereon the bobbin is rotatably mounted.

The spool as it leaves the hands of the manufacturer comprises the cylindrical portion 1 with the thread or twine 2 wound thereon. The metal end head portions 6 and 7 with the felt washers 11 and 12 encircling their central projections are then applied thereto when the bobbin may be inserted in the shuttle, the shaft 5 entering within the spool portion 1 and the end heads as shown in Fig. 2 when the shuttle with the bobbin can be inserted in the sewing machine, the bobbin rotating upon the shaft 5 in the usual way. Each of the end heads comprises a side portion 8 from which extends a projection 9 adapted to fit rather tightly within the end of the tube portion 1 and a felt washer 11 for producing a cushion at the inside of the head, while the hole 10 extending entirely through the head is of a diameter such as to give a running fit about the shaft 5. Each metal end head portion is a single integral piece so that there is no danger of the side falling off as where the side and projection are separate pieces.

To prepare the spool as it comes from the

manufacturer to be entered within the shuttle, the end heads 6 and 7 are put in place at either end by telescoping the projections 9 within the ends of the spool portion 1. The bobbin is then placed in position within the shuttle by entering the shaft through the end heads and spool portion.

It will be seen by reference particularly to Fig. 2 that the spool portion 1 which is usually 10 of material such that it has not suitable wear resisting properties and is not adapted to accurately hold the bobbin in position, does not come in contact with the shaft 5, but the bearing surface for the bobbin is provided by the end heads which are formed of harder and greater wear resisting material which can be fitted with sufficient accuracy to the shaft upon which the bobbin turns and will not deteriorate with undue rapidity 15 in use. The material of the end heads is preferably of some suitable metal such as brass but might be of hard fibre or other suitable substance.

It is also to be observed that the felt 20 washer at each end of the bobbin provides a cushioning means inside the head as hereinbefore referred to.

While the invention has been illustrated in what is considered its best application 25 it may have other embodiments without departing from its spirit and is not therefore 30

limited to the structure shown in the drawings.

What I claim is:

1. The combination with a spool comprising 35 a cylindrical portion on which the thread is wound and end heads secured thereto of resilient washers on the inside of said heads between said heads and the thread position.

2. The combination with a shuttle having a bobbin recess, and a bobbin supporting shaft in said recess, of a bobbin within said recess and rotatably supported upon said shaft, said bobbin comprising a hollow cylinder upon which the thread is wound and end heads having projections telescoping within the ends of said cylinder and axial openings for the reception of the shaft, said shaft extending within said cylinder and openings, and a washer surrounding at least one of said projections.

3. A bobbin comprising a cylinder of one material and end heads of different material, each of said end heads having projections telescoping into the ends of said cylinder and a resilient washer at the inner side of at least one of said heads.

In testimony whereof I have signed this specification this 25th day of August, 1922.

WILLIAM R. BERRYMAN.
